UNITED STATES PATENT OFFICE

GEORGE E. R. ROTHENBUCHER, OF NEW YORK, N. Y.

SMOKE-CONSUMING FURNACE.

No. 872,873.

Specification of Letters Patent.

Patented Dec. 3, 1907.

Application filed December 1, 1906. Serial No. 345,960.

To all whom it may concern:

Be it known that I, GEORGE E. R. ROTHENBUCHER, a citizen of the United States, residing in the borough of Brooklyn, county of 5 Kings, city and State of New York, have invented certain new and useful Improvements in Smoke-Consuming Furnaces, of which the following is a specification, reference being had therein to the accompanying 10 drawings, in which—

Figure 1 is a horizontal sectional view of a furnace provided with my invention; Fig. 2 a transverse vertical sectional view thereof; Fig. 3 a front view; Fig. 4 a transverse vertical sectional view of the steam and air injecting means; Fig. 5 a longitudinal sectional view of the steam and air injecting means; Figs. 6 and 7 detail views of the fan hub.

The main object of the invention is to provide an improved furnace in which cheap fuel, such as shavings and refuse from saw mills, soft coal, &c., will be entirely consumed within the fire box, or combustion chamber, thereby preventing the escape of carbon particles in the form of smoke.

Another object of the invention is to provide means whereby exhaust steam and air may be delivered under a suitable pressure, and in the proper direction, over the fire in 30 the fire box and upward through the bridge wall to promote complete combustion.

A further object of the invention is to provide simplified and improved means operated by exhaust steam for supplying air to the 35 fire box.

Other objects of the invention, relating more particularly to details of construction, will be fully hereinafter described and particularly pointed out in the claims.

The particular construction of furnace shown in the drawings and described herein, but not claimed, is embodied in my copending application for patent for furnace, filed 40 March 12, 1907, Serial Number 362,048.

Referring to the various parts by numerals, 45 1 designates the boiler front, 2 the fire box and 3 the bridge wall. In the side walls of the furnace, a suitable distance above the grate 4, are steam and air flues 5, one of said flues being in each wall and extending the 50 full length of the fire box, parallel with the side walls thereof. Each of these flues is formed of three interlocked cast iron tubular sections or boxes 6 which open into each 55 other and whose inner surfaces are flush with the inner surface of the side wall of the fur-

nace. On the inner faces of these tubular sections are formed heating and deflector walls 7 which incline inward and rearward at an angle of forty-five degrees with respect to 60 the side wall of the furnace. Each section 6 is formed with slits or openings 8 which extend inward through the wall of the section from the inner end of the deflector wall 7 and at the same angle as said deflector wall. The 65 result of this is that thin vertical streams of mixed exhaust steam and air flow outward through said slits over the deflector walls and into the fire box. The deflector walls form the forward sides of angular projections 70 on the face of the sections 6, said projections being V-shaped in plan view. As these projections extend into the fire box it will be readily seen that they become highly heated and that the deflector walls serve as heating 75 surfaces for the mixed exhaust steam and air.

The bridge wall 3 is formed at its upper edge with a cellular structure having horizontal passages 9, said passages being formed by 80 suitable brick work. In the bridge wall along the base of these passages is arranged a transverse flue or pipe 10 which connects at its ends with the rear ends of the side flues 5. The flue 10 is very much smaller in capacity 85 than the flues 5 and is connected to these latter flues near the bottoms thereof. The object of this is to hold the larger proportion of steam and air in the flue 5 and to permit only a small portion thereof to pass into the flue 90 10. This latter flue or pipe is perforated, said perforations opening into the passages 9 so that the steam and air will be directed into said passages to there mingle with the flame and products of combustion from the fire 95 box. It will be readily understood that the pipe 10 will become highly heated and will thereby act as a superheater to the mixed air and steam, and that said mixture will pass into the passages 9 in a very dry condition 100 and will assist greatly in promoting combustion.

To supply air and exhaust steam to the forward ends of the flues 5, I provide for each flue a tubular conveyer 11 and mount therein 105 suitable steam-driven air-driving means, by which air will be forced into the flue through the conveyer together with the proper proportion of exhaust steam. The forward end of each conveyer projects beyond the front wall of the furnace a suitable distance, said conveyer being secured to the furnace wall 110
